UNITED STATES PATENT OFFICE

SIMON W. WARDWELL, OF PROVIDENCE, RHODE ISLAND, ASSIGNOR TO
UNIVERSAL WINDING COMPANY, OF PORTLAND, MAINE, A CORPO-
RATION OF MAINE.

WINDING-MACHINE.

No. 806,221.

Specification of Letters Patent.

Patented Dec. 5, 1905.

Application filed May 24, 1902. Serial No. 108,825.

To all whom it may concern:

Be it known that I, SIMON W. WARDWELL, a citizen of the United States, residing at Providence, county of Providence, and State of Rhode Island, have invented a new and useful Improvement in Winding-Machines, of which the following is a specification.

My invention relates to winding-machines, but more especially to cone-winding machines.

The object of my invention is to provide adequate devices for preventing the bulging which is inherent in certain materials, like wool and worsted, which are of a peculiarly slippery texture and cannot be readily retained in place by the usual expedients of winding.

The mode of operation and structure of my invention with one form of modification thereof are described in the following specification and illustrated by the accompanying drawings, of which—

Figure 1 represents a portion of a winding-machine, showing the thread-guide and traverse-frame and the relation of my invention thereto; Fig. 2, an end view of the outer disk or head for supporting the cop, showing the preferred means of removably attaching it to the cop-tube carrier; Fig. 3, a section of the outer head, taken on the line A A, Fig. 2, and showing the preferred device for securing in place the said outer head. Fig. 4 is a sectional view of the tube-holding device extending through the ring m on the line B B, Fig. 8, showing the devices whereby the tube is retained by or disengaged from the tube-holder and also an alternative means for retaining the head n; Fig. 5, an end view showing in operative position the alternative means for retaining the head n; Fig. 6, an end view of the tube-carrier a looking in the direction indicated by arrow C; Fig. 7, a view of the inner head of the carrier removed, also looking in the direction indicated by arrow C; Fig. 8, an end view of ring m looking in the same direction.

One preferred form and arrangement of my invention is shown applied to a tube-holding device such as is described in my Patent No. 690,493, recently issued, in which the tube-carrier is formed with expandable staves or segments, whereby the tube is secured.

The tube-holder is arranged between heads or disks b n, the latter at least removable, and the guide 8 traverses at each movement the length of the holder in contact with the cop, so as to gradually move outward as the package increases in diameter, the heads preventing any such lay or disposition of the thread as would result in a cop with bulging ends. To this end the traverse-frame which supports the guide is shortened, so that it may pass between the heads as it swings in and out and afford a support on which the guide may travel the length of the package between the heads at each movement.

While the heads or disks may be mounted and secured in any suitable manner on the spindle, I prefer to use the means I will now describe.

On the base end of the tube-carrier a, as shown in Fig. 4, is mounted a disk or head b, fixedly secured to alternate segments c, leaving the intermediate segments d free to be expanded and secured from turning by the two projections e, which engage the holes f in two of the segments c.

Mounted on the winding-shaft of the machine to which the tube-carrier is secured is the sleeve g, Fig. 4, adapted to be shifted longitudinally thereon by means of the lever h, Fig. 1, to effect the expansion of the free segments d, which latter have internal projections i to engage the ring j of the sleeve g aforesaid. The segments c have no internal projections, and hence are not affected by the ring j. (See Fig. 6.)

Between the segments c the head or disk b is cut away with radial recesses k to permit the passage of radial projections l of the ring m, mounted to turn freely on the sleeve g. The free segments d are shortened, admitting between the segments c the projections l of the ring m, thus effecting rotative engagement of the said ring and the tube-carrier a, which engagement is constant. The segments d are sufficiently shorter than the segments c to permit the ring m to be passed and protruded through the head b. This is for the purpose of disengaging the completed package from the tube-carrier. The tube on which the package is wound when secured to the tube-carrier extends up to the head b, and the projections l as they protrude through the

head *b* engage the tube after it has been released from the segments *d* and shift it on the carrier to disengage it therefrom.

The outer head *n* is provided with a hub *o*, 5 by which it is mounted on a stud or projection *p* of the tube-carrier. The recess *q* accommodates the portion of the tube which projects from the end of the package, thus permitting the head *n* to be brought close to 10 the end of the package.

To provide for placing the cop-tube upon the carrier and for removing the completed package therefrom, the head *n* is so secured as to be easily removed. This may be accomplished by various suitable means—as, 15 for instance, one of those now to be described.

As shown in Figs. 2 and 3, at the outer end of the hub *n* is supported a cup-shaped member or cap *r*. The latter is rotatable on its 20 bearing *s*, which is a portion of the hub *o*, formed eccentric with the axis of the head *n* and the tube-carrier. The cap *r* is retained longitudinally by a pin *t*, fast in the hub *o* and engaging a suitable slot in the cap. In the 25 end of the cap *r* is a circular opening *u* of appropriate size to slide freely over the tip 10 of the projection *p*, which is slightly reduced in diameter from the main portion on which the head has its bearing. The opening *u* is of less 30 diameter than the main portion of the projection *p*, so that the latter serves as a stop to limit the extent to which the head *n* can be slid on its bearing. Between the main or bearing portion and the tip of projection *p* is a circumferential 35 channel *v* of appropriate width to receive the end of the cap to retain the head *n* in position. The opening *u* is formed eccentric to the axis of the bearing *s*, on which the cap *r* turns, and so related thereto that the turning of the cap 40 will bring it in line with the axial hole in the hub *o*. At the inner end of the cap is a recess or channel *w*, adapted to receive a coiled spring *x*, secured with one end fast in the cap and the other in the hub *o*. The spring *x* 45 maintains the cap normally in the position indicated in Fig. 2, with the opening *u* eccentric to the tip of the projection *p* and the annular flange *y* in engagement with the groove *v*. The action of the spring is limited by the pin 50 *t* contacting with the end of its slot. The latter is of such length that its opposite end contacts with said pin to prevent the turning of the cap beyond a point where the opening shall be concentric with that of the hub. The 55 periphery of the cap is normally concentric with that of the hub and may be knurled to afford a good handhold.

The operation of the device is as follows: After the cop-tube has been placed upon the 60 carrier *a* the cap *r* is turned on its bearing on the hub *o* until the opening *u* registers with that in the hub. The head is then slid onto the projection *p* until the end of the cap contacts with the end of the main portion of the

projection *p*, at which point the flange *y* of 65 the cap is forced by the spring into the groove *v*. The engagement of the cap with the groove retains the head in position. To remove the head *n* at the completion of the winding, it is necessary only to turn the cap until its opening is concentric with and free to slide over 70 the tip of the projection *p*.

A modification of the retaining devices is shown in Figs. 4 and 5, in which the head *n* is retained by a spring-catch *2*, which is adapted to simply move transversely on the end of the hub *o*. 75

The use of removable retaining-heads is not *per se* new in the art of winding, a usual mode of winding some cords having been to wind 80 between heads and before removing the latter to bind together the material wound by a series of ties. In such devices, however, the heads or flanges formed a part of a removable spool, which latter must be disassembled to 85 remove the material wound and reassembled and replaced in the machine before again commencing the winding.

By means of my device it is possible to wind upon the usual inexpensive paper tube, and 90 as the heads *b* and *n* constitute really a part of the tube-carrier *a* and are used in conjunction with the devices for quickly securing the tubes or doffing the packages materials can be wound that could not otherwise be wound 95 expediently, if at all, for scarcely any more time is consumed in removing the head *n* than is required to remove a tube or package alone.

The device is particularly valuable in winding certain materials which are so slippery and elastic that they cannot be wound without excessive bulge. By winding such materials between heads in the manner described well-formed cops are wound, which when released retain their shape indefinitely. 100

Without limiting myself to the precise form of structure or arrangement and correlation of the parts employed, I claim as my invention— 105

1. The combination in a winding-machine, 110 of a tube-carrier, retaining-heads on the tube-carrier, a thread-guide adapted to reciprocate between the said heads, and a movable support on which the guide reciprocates adapted to swing between the said retaining-heads to 115 and from the carrier.

2. The combination with a winding-spindle, 120 of retaining-heads mounted on the spindle, thread-guide, a frame and support thereon on which the said guide is reciprocated, said support adapted to swing to and from the spindle between the heads to permit the guide to bear on the surface of the package for the length of the latter at all times during the winding.

3. The combination with a winding-spindle, 125 of fixed and removable heads on the spindle, a frame, a guide-support carried thereby enterable between the heads, and a guide adapted

to reciprocate between the heads on said support.

4. The combination with a rotatable spindle, of a bearing therefor at one end, a head or disk near said end only, means for securing it to turn with the spindle, means for retaining a removable cop-tube on said spindle, a second head or disk, and means for connecting it detachably to the outer free end of the spindle.

5. The combination with a rotatable spindle, of a bearing therefor at one end, a head or disk near said end, means for securing it to turn with the spindle, means for retaining a removable cop-tube on said spindle, a second head or disk, means for connecting it detachably to the outer end of the spindle, a swinging frame arranged to swing between said disks, a guide-support on the frame, and a guide carried by said support.

6. The combination in a winding-machine of a tube-carrier, formed with a recess at one end and with expansible segments surrounding the recess, a disk fixedly secured to certain of the segments and with the remaining segments left free to be expanded, internal projections on the free segments, a sleeve with a projecting ring to engage the said projections and a lever whereby the sleeve is shifted to expand the segments or permit them to contract.

7. The combination in a winding-machine of a tube-carrier formed with a recess at one end and with expansible segments surrounding said recess, a disk fixedly secured to a portion of the segments and having radial recesses between the supporting-segments, internal projections on the free segments whereby they may be expanded, a sleeve movable longitudinally to engage said projections to expand the free segments, and having radial projections adapted to pass through the radial recesses in the disk aforesaid, and a lever engaging said sleeve whereby it may be shifted in the manner and for the purpose substantially as described.

8. The combination in a winding-machine of a tube-carrier having expansible segments, a disk mounted on the carrier and a sleeve movable longitudinally within the carrier to expand the segments and having portions adapted to pass through the disk for the purpose and in the manner substantially as described.

9. The combination with a tube-carrier, of a head removably mounted on the tube-carrier, and a spring-catch mounted on said head to engage the tube-carrier and locate the head longitudinally thereon, substantially as described.

10. A cop-holder for a winding-machine comprising a tube-carrier α , a disk b mounted on the tube-carrier, expansible segments d of the tube-carrier, a sleeve g longitudinally movable within the tube-carrier to expand the said segments, and having a ring m adapted to be

passed through the disk b , and a handle h to shift the sleeve g and its ring m , a head n mounted on the outer end of the tube-carrier and removable therefrom, and a spring-catch to secure the removable head n on the tube-carrier, substantially as described.

11. The combination with the tube-carrier of a winding-machine, of a removable head therefor having a hub and a rotative spring-operated catch mounted on said hub, for securing said head to or releasing it from the tube-carrier.

12. A device for securing a removable head to the tube-carrier of a winding-machine consisting of a projection of the tube-carrier on which the head is mounted, a cap secured to the head and rotatively mounted eccentric with the axis of the head, an opening in the end of the cap to receive the said projection, eccentric with the cap and normally eccentric with the axis of the head to engage the cap with the projection.

13. The combination with the removable head of a tube-carrier, of a retaining-cap having a bearing thereon eccentric with the axis of the head, means for retaining the cap on its bearing, an opening in the end of the cap eccentric with the axis of its bearing, and a spring for maintaining the opening normally eccentric with the axis of the head.

14. A device for securing a removable head on a tube-carrier, comprising a hub on said head, a circular portion of the hub eccentric with the axis of the head, a cap mounted to turn on said eccentric portion, means for retaining the cap longitudinally on the head, an opening in the end of the cap eccentric with the bearing of said cap and adapted to receive the end of a stud, a circular groove in the stud, adapted to be engaged by the end of the cap, and means for normally maintaining the cap with its opening eccentric with the axis of the head and in engagement with the said stud.

15. The combination with a removable head for a cop-tube carrier, of a projection of said carrier serving as a bearing for the head, a tip on said projection of less diameter than the bearing portion, a peripheral groove in the projection between the bearing portion and the tip, a cap, a bearing on the head for the cap, eccentric with the axis of the head, means for retaining the cap on its bearings, and for limiting its movement, an opening in the end of the cap, adapted to pass over the tip but engaging the end of the bearing portion of the projection, and a spring for maintaining said opening eccentric with the axis of the head to engage the end of the cap with the groove.

16. The combination in a cop-retaining head for a winding-machine, with a hub on said head, of a cap rotatively mounted on the hub eccentric with its axis, having a peripheral slot and a hole eccentrically located in the end of the cap, adapted to be shifted into line with the axis of said hub by rotating the cap, a pin

mounted in the hub aforesaid engaging the peripheral slot of the cap to retain it longitudinally in position and limit its rotative movement, a projection serving to support the said head, a tip to said projection adapted to enter the opening in the cap and a coiled spring engaging the hub and cap to normally maintain the cap in engagement with said tip.

In testimony whereof I have signed my name to this specification in the presence of two subscribing witnesses.

SIMON W. WARDWELL.
